UNITED STATES PATENT OFFICE.

HARRY H. STYLL AND HAROLD K. PARSONS, OF SOUTHBIDGE, MASSACHUSETTS.

LENS-SLOTTING MACHINE.

1,220,287.

Specification of Letters Patent. Patented Mar. 27, 1917.

Application filed December 18, 1915. Serial No. 67,075.

To all whom it may concern:

Be it known that we, HARRY H. STYLL and HAROLD K. PARSONS, citizens of the United States, residing at Southbridge, in the county of Worcester and State of Massachusetts, have invented certain new and useful Improvements in Lens-Slotting Machines, of which the following is a specification.

10 Our invention relates to improvements in lens slotting machines, and has for its leading object the provision of a simple, inexpensive and durable construction, by the use of which a slot of any desired size or shape 15 may be formed in the lens, and in any desired relation to the geometrical axes thereof.

15 A further object of our invention is the provision of an improved device of this character which may be used as a chart or 20 protractor for laying out the geometrical axis, direction of slot, variety of slot or the like, if desired, in addition to serving as a slotting guide.

25 Other objects and advantages of our improved construction should be readily apparent by reference to the following description taken in connection with the accompanying drawings, and it will be understood that we may make any modifications in the 30 specific details of construction shown and described within the scope of the appended claims without departing from or exceeding the spirit of our invention.

35 Figure I represents a side elevation of the simpler construction of our device.

Fig. II represents a similar view with a centering attachment applied thereto.

Fig. III represents a top plan view of the construction illustrated in Fig. II.

40 Fig. IV represents a bottom plan view of the lens supporting table and centering attachment.

Fig. V represents a plan view of a modified construction of our invention.

45 Fig. VI represents a view partially in section and partially in perspective of this construction.

Fig. VII represents a plan view of a form of lens having a dove-tail shape of slot 50 formed therein.

Fig. VIII represents a similar view of a lens having a pair of converging slots formed therein.

55 Fig. IX represents a fragmentary view of a lens having a different slot.

Fig. X represents a similar view of the lens with a straight slot.

Fig. XI represents a view of the lens having a channel or countersink formed in one face thereof.

Fig. XII represents a view of the combined notched and drilled lens.

In the drawings in which similar characters of reference are employed to denote corresponding parts throughout the several views, the numeral 1 designates the main frame or base of the machine, having rising therefrom the journal bearings 2 for the spindle 3, carrying the abrasive or cutting disk 4, while rising from the base 1 a suitable distance from the periphery of the disk 4 is the standard 5 preferably terminating in the socket 6 to receive the cap 7 for clamping in position the ball or universal joint member 8 on the underside of the lens supporting table 9. This ball may be either directly clamped in the socket, or the lower portion 6 of the socket may be resiliently forced upward into engagement with the ball, as by a spring 10, which will at all 80 times hold the ball tightly clamped and yet permit of shifting of the table without loosening of the cap 7 as is otherwise necessary.

In the form of our invention illustrated in Figs. I and III for example, we have shown 85 as carried by the neck 11 of the ball 8, the table 9, which in Fig. III is shown as bearing on its upper face a plurality of longitudinally extending lines or scorings 12, the central one being designed to indicate 90 the position of the geometrical axis of the lens, and the lines at each side denote the variations above or below center, as may be desired. In addition there is formed at one edge of the table the notch 13, while disposed inwardly thereof on the central line 12 is a representation of a circle or aperture 14 for use in the laying out of various types of notched or slotted lenses. In addition the face of the table bears at each side 160 slightly off center a diagonally disposed line or designation 15, having a short heavy portion and a lighter continuation extending substantially to the other edge of the table. These are useful in the laying out of special 105 bevel slots for particular forms of lens attachments, inasmuch as a lens marking pencil may be employed to indicate on the lens the length of the short heavy portion of the line, and an additional mark placed at the 110

opposite edge of the lens and on the same straight line, when the lens is turned with the points marked at its two edges coinciding with the center line 12 and moved outwardly along that as a guide until the correct depth of slot as indicated by the heavy portion of the line has been formed.

In addition to the several series of straight lines just described we may if desired place 10 on the table 9 at any desired relation to the edge thereof one or more ellipses 16, denoting various standards, sizes and shapes of lenses, so that by placing of a lens with its edge fitting one of these ellipses the geometrical axis will be caused to coincide with the 15 axis designating line on the table.

If preferred, in place of making use of ellipses or the like for positioning the lens to determine its exact geometrical axes, we 20 may make use of an automatic centering device, such as that particularly illustrated in Fig. IV for example. This construction comprises a pair of arms 17 united as by a hollow rivet 17' which is slidably mounted 25 on the neck 11 of the table support, the arm 17 having projecting thereabove the lens edge engaging pins 18 slightly undercut as at 19, so that they will satisfactorily hold the lens against the table, two of the pins 30 having depending handle portions 20 which may be engaged and pressed to separate the pair of lens engaging pins 18 at each end of the lens against the tension of the impelling spring or springs 21, as should be readily 35 understood by reference to Fig. IV. The hollow rivet if desired may have frictional engagement with the post 11 to aid in retaining the parts in either raised or lowered position as desired. It will be understood 40 that the table 9 is provided with arcuate slots 22 to accommodate the pins 18 while a follower 23 slidably mounted in a guide way on the under side of the table, and forced inward by a light spring 24 fits between the 45 arms 17 to insure centering thereof and prevent their bodily rotation about the member 11 as a pivot without in any way interfering with their relative adjustment.

It will thus be seen that by pressing together of the lower portion 20 of the pins the upper ends 18 of the pair at each end of the table may be separated to satisfactorily receive a lens therebetween and the entire device pressed upward into operative position. On the other hand, after the lens 55 has been properly centered and marked, etc., the device may then be disengaged from the lens and slid downward leaving a smooth working surface to the table.

In the form of the invention illustrated in Figs. V and VI we employ the supplemental lens clamping table 29 provided with a depending pin 26 adapted to engage in one of the apertures 25 formed in the main table 9. 65 If desired, in order to facilitate varying of

the position of the pivot pin 26 relative to the lens clamp table 29 this pin may be carried by a guide 27 sliding in a groove 28 on the under side of the table 29. In either event the table has rising therefrom a suitable lens centering device such as the pair of stationary pins 30 at the front edge thereof and the pivoted arm 31 bearing the lens clamping pins 32 held in operative position as by the spring 33, the pins 32 under the influence of the spring 33 clamping the lens and securely holding it forward in centered position and against the pins 30, as illustrated.

It is to be noted in connection with the first described form of our invention that the bearings 2 for the spindle 3 are swingingly supported on the base 1, and that consequently the shaft or spindle 3, and the cutting disk 4 carried thereby may have an in and out movement controlled as by the operating lever 34. As a result of this arrangement either the lens 35 to be cut or slotted may be moved inwardly into engagement with the cutting disk 4 or the lever 34 90 may be depressed to bring the disk forward into cutting relation to the table 9. This forward feed may be either manually controlled by pressure on the lever 34 or may be a matter of automatic operation as by a spring 36, serving to draw the cutting disk toward the lens, a stop 37 in either event being preferably employed to limit the depth of the cut.

In that form of the invention illustrated in Figs. V and VI, should it be desired to form the type of aperture illustrated in Fig. VII for example, the pin 26 would be set in the aperture 25 adjacent the edge of the table 9, the lens being clamped with its edge overhanging the supplemental table 29; the cutting disk is moved into engagement therewith first forming a substantially straight cut, after which the table may be given a slight swinging movement about the pivot 110 26, which being located almost beneath the edge of the lens, will cause a widening on the inner portion of the cut to a wedge form, substantially as illustrated in Fig. VII. On the other hand, when it is desired to form 115 slots such as illustrated in Fig. VIII for example either the table 29 may be held stationary upon a table 9 and the two tables swung together about the ball 8 as a pivot center, so that first one and then the other 120 of the diagonally extending slots may be cut, or the table 9 may be left stationary, the pin 26 set at its inner aperture 25 and the supplemental table 29 swung about the pin 26 as a center for the formation of the two 125 diagonal slots.

In case it is desired to form an ordinary straight slot in the lens, either the supplemental table 29 may be slid forwardly on the table 9, the member 27 acting as a guide,

or the disk may be moved toward the lens, as may be preferred by the individual operator.

From the foregoing description taken in connection with the accompanying drawings, the construction and operation of our improved machine should be readily apparent, and it will be seen that we have provided a simple and efficient machine embodying a lens supporting table adapted in addition to serve as a protractor and guide in laying out the various types of notches or slots which may be formed by the machine, and which table is universally adjustable to facilitate either slotting or by tilting, a surface-grooving of a lens and at any desired angle or angles, and that we have in addition provided centering attachments for quickly and accurately positioning the lens so that the geometrical axis thereof will have the desired relation to the table, which attachments may be readily applied to and used in conjunction with or removed from the main table of our machine, and it will further be noted that we have provided an improved machine in which either the lens may be moved toward the cutting disk, or the cutting disk toward the lens, as desired, and in which various desired adjustments of the lens relative to the cutting disk may be readily made.

We claim:

1. In a device of the character described, the combination with a lens supporting table, of a depending post carried thereby, a sleeve slidably mounted on the post, arms pivoted

on the sleeve and movable therewith, means for drawing the outer ends of the arms together, and pins projecting upwardly from the ends of the arms, the table being provided with arcuate slots adapted to receive 40 the pins and allow their upper ends to project above the table when the sleeve is moved upwardly on its post.

2. In a lens slotter, the combination with a stationary but adjustable lens supporting 45 table, of a cutting disk for slotting the edge of the lens while on the table, means for automatically shifting the disk in the direction of the table to form the slot in the edge of the lens, and adjustable means for limiting the movement of the disk and thus the depth of the slot formed in the lens.

3. In a device of the character described, the combination with a base, of a support rising therefrom, a lens table adjustably 55 mounted on the support, a standard pivoted to the support and bearing a cutting disk at its upper end, automatic means for swinging the standard toward the support to bring the disk into operative engagement 60 with a lens on the table, an adjustable stop for limiting the approach of the disk toward the table, and manually operable means for controlling the movement of the disk irrespective of the automatic control therefor. 65

In testimony whereof we affix our signatures.

HARRY H. STYLL.
HAROLD K. PARSONS.
